(57) CLAIM

The ornamental design of a shovel with an inverted tip, substantially as shown and described.

DESCRIPTION

FIG. 1 is a front perspective view of a shovel with an inverted tip in accordance with the present invention; FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines represent the boundaries of the claim and form no part of the claimed design.
